U.S. Appl. No. 29/414,544, filed Feb. 29, 2012, entitled "Light".

Primary Examiner — Cynthia Ramirez

Assistant Examiner — Llorellys Martinez-Rivera

(74) *Attorney, Agent, or Firm* — Saidman DesignLaw Group, LLC

CLAIM

The ornamental design for a light, as shown and described.

DESCRIPTION

FIG. 1 is a front perspective view of a light showing our new design;

FIG. 2 is a front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof;

FIG. 8 is a rear perspective view thereof; and,

FIG. 9 is a front perspective view thereof, with the strap shown in a closed configuration.

The broken lines shown in FIGS. 1-9 illustrate portions of the light which form no part of the claimed design.

1 Claim, 1 Drawing Sheet
